ELECTROMAGNETIC RELAY

William A. Ray, Los Angeles, Calif.

Application December 5, 1942, Serial No. 467,965

3 Claims. (Cl. 175—336)

My present invention relates to electromagnetic relays, of the low energy-consumption type, for operating condition controlling means such as electrical contacts or pilot-valve jets.

In my copending application, Serial No. 456,358, filed August 27, 1942, now Patent No. 2,358,828, granted September 26, 1944, of which the present application is a continuation in part, I have disclosed an electromagnetic operator, of the series working-gap type, the energy consumption of which is very small in comparison with that of conventional electromagnetic operators capable of performing equivalent work; the improvement residing mainly in the provision of a core having, at its ends, enlargements forming pole faces which are considerably greater in area than the cross-sectional area of the body of the core. The improved operation of that device is mainly due to the fact that, when the flux density in the core (produced by a weak magnetizing force) is at a point considerably below the knee of the magnetization curve for the core material, the flux density in the large-area pole face is substantially the same as that which could be produced by the weak magnetizing force if the cross-sectional area of the body of the core were not reduced; reduction of the body area making possible the use of a coil winding of small mean turn diameter and correspondingly small electrical resistance. It is a general object of the present invention to apply similar principles to provide a low energy-consumption electromagnetic relay.

More specifically, it is an object of this invention to provide an electromagnetic relay comprising a U-shaped core having, at the ends of its side arms, means defining pole faces, the areas of which are considerably greater than the cross-sectional area of the main body portion of the core.

Another object is the provision, in an electromagnetic relay of the character described, of a bracket for mounting the condition controlling means operated by the relay; which bracket is supported by the enlarged pole-face-defining means.

Another object is to reduce the actual length of an elongated U-shaped core without reducing its effective length, this object being achieved by forming the core as a continuous double-U.

Other objects and advantages of the invention will be found in the description, the drawing, and in the claims; and for full understanding of the invention reference may be had to the following detailed description and accompanying drawing, wherein:

Figure 1 is a side elevation of an electromagnetic relay embodying my invention;

Figure 2 is an end elevation, as viewed from the left, of the relay shown in Figure 1;

Figure 3 is an enlarged fragmentary view, in perspective, showing constructional details of the relay; and

Figure 4 is a view, in perspective, of a modified form of core for the relay.

10 In Figs. 1-3 of the drawing, the numeral 11 indicates a U-shaped electromagnet core, around the side arms of which are energizing coil windings 12 and 13. Mounted on the free ends of the side arms of the core are like heads 14 and 15 formed from strips of magnetic sheet material. As is best seen in Fig. 3, the end portions 16 of each strip are bent backwardly parallel to the middle portion 17 in spaced relation thereto, and their extremities are rebent outwardly at right-angles to the middle portions of which arms are curved to conform to the cylindrical surface of the core arm, to which they are clamped at their sides by screws 18. In the process of formation of heads 14 and 15, the strips are inserted through slots 20 punched in a bracket 21, of non-magnetic material such as brass, so that when the heads are formed and clamped to the core arms the bracket is rigidly supported thereby.

30 The outer surfaces 22 and 23 of the heads 14 and 15, respectively, define the pole faces of the electromagnet. In the particular construction shown, the area of each pole face is approximately ten times that of the cross-sectional area of its respective core arm, as is clearly seen in Fig. 2. The ratio of the area of the pole face to the cross-sectional area of the "body" of the core (the portion on which the coil is wound) may be increased when the material of the core and

40 head is of high permeability and the flux density is very low—such as can be produced by an ordinary pilot-burner-heated thermoelectric generating device. When the flux density is higher, but still considerably below the knee of the magnetization curve for the core material, better results may be produced by somewhat decreasing the area ratio.

50 Fulcrumed on the pole face of the upper core head 14 toward the top end of the same is an armature 24, the armature being formed to provide a transverse knife-edge 25 which bears in a notch 26 cut in the surface of the core head; lateral movement of the armature being prevented by portions 27 struck up from the edges 55 of the bracket 21. Carried by the bent lower end

portion of the armature is a contact 28 which is engageable with a relatively fixed contact 29, insulatingly mounted on the bracket 21, when the armature is attracted toward the pole face 23 upon passage of current through the coil windings 12 and 13. Biasing the armature away from the pole faces is a spring 30 compressed between the armature and a turned-over upper end portion 31 of bracket 21; and limiting movement of the armature in its biased direction is a stop-screw 32 threaded in a turned-over lower end portion 33 of the bracket. For electrically connecting the contacts of the relay in a circuit, the armature is provided with a flexible pig-tail 34, and the screw portion of the fixed contact 29 is threaded in the insulated eyelet of a terminal lug 35.

While the general construction shown in Figs. 1-3 is that preferred, it is not essential that the pole face on which the armature is pivoted be enlarged, especially if the armature is maintained in good flux-transfer relation to that end of the core as by a resilient strip of magnetic material joining it permanently to the core; however, in the construction shown, both of the pole faces are effective in the attraction of the armature—the width of the armature being the same as that of the pole faces so that the free portions of the armature adjacent the pole faces are coextensive therewith and hence relatively large. While the armature is shown fulcrumed directly on the pole face, in some cases it may be separated therefrom by a minute air-gap (provided by non-magnetic material) in order to prevent magnetic sticking; such separation being desirable when the area of the bearing surface of the armature is relatively large.

In Fig. 4 is shown a modified form of core for the relay. This core consists of a pair of U-shaped members 36 and 37 joined together at one of their respective ends by a strap 38 to form a double-U; all these parts, of course, being of magnetic material. It will be apparent that the core is effectively an elongated U re-bent in the middle to provide four side arms for the coil winding 39. Without increasing its actual length, the effective length of the core is thus greatly increased so that the coil winding may be composed of many turns of small mean diameter.

whereby its electrical resistance is considerably reduced. When this core is employed in the construction of a relay of the type shown in the other figures, it is provided with heads similar to those indicated at 14 and 15 in Fig. 1.

While I have herein shown and described specific embodiments of my invention, I wish it to be understood that modifications may be made without departing from the spirit of the invention, and that I intend therefore to be limited only by the scope of the appended claims.

I claim as my invention:

1. In an electromagnetic operator: a U-shaped core; an energizing coil winding for said core; means, of magnetic sheet material, at the free end of each of the side arms of said core and defining a pair of spaced-apart and substantially coplanar pole faces; each of said pole-face-defining means being formed to provide a flat first portion, one surface of which defines said pole face, a second portion parallel to and spaced from said first portion, and an end portion at right-angles to the other portions and attached to the respective side arm of the core; a generally-rectangular bracket of non-magnetic material received between the spaced-apart first and second portions of both of said pole-face-defining means and rigidly supported thereby; and an armature cooperable with said core and mounted by the aid of said bracket.
2. In an electromagnetic operator: a U-shaped core, an energizing coil winding for said core, means of magnetic material at the free end of each of the side arms of the core and defining a pair of enlarged and substantially coplanar pole faces, a bracket of non-magnetic material, each of said pole-face-defining means being formed to receive within it and tightly hold a portion of said bracket, and an armature cooperable with said core and mounted by the aid of said bracket.

3. An electromagnet comprising an elongated U-shaped core the free ends of which form a pair of pole faces, said core being rebent in a U-shape to form a double-U having four side arms; and a coil winding around each of said side arms for so energizing the core that said pole faces are at opposite polarities.

WILLIAM A. RAY.
